(57) **CLAIM**

The ornamental design for a virus-shaped pet toy, as shown and described.

DESCRIPTION

FIG. 1 is a front perspective view of the virus-shaped pet toy, showing the new design;

FIG. 2 is a rear perspective view of the virus-shaped pet toy thereof;

FIG. 3 is a front view of the virus-shaped pet toy thereof;

FIG. 4 is a rear view of the virus-shaped pet toy thereof;

FIG. 5 is a left side view of the virus-shaped pet toy thereof;

FIG. 6 is a right side view of the virus-shaped pet toy thereof; and,

FIG. 7 is a top plan view of the virus-shaped pet toy thereof. The broken lines illustrate portions of the virus-shaped pet toy that form no part of the claimed design.
